UNITED STATES PATENT OFFICE.

EMILE E. BOUCHARD, OF BURLINGTON, VERMONT.

CURTAIN FOR AUTOMOBILES.

Application filed April 4, 1921. Serial No. 453,196.

To all whom it may concern:

Be it known that I, EMILE E. BOUCHARD, a citizen of the United States, residing at Burlington, in the county of Chittenden and State of Vermont, have invented certain new and useful Improvements in Curtains for Automobiles; and I do declare the following to be a full, clear, and exact description of the invention, such as will enable others skilled in the art to which it appertains to make and use the same.

This invention relates to improved curtains for use in connection with automobiles, and one object of the invention is to provide a curtain so constructed that it may be mounted in the top portion of the automobile above the entrance door of the body and moved vertically into and out of an operative or closing position, the curtain 20 when in an inoperative position being slid upwardly and inwardly and positioned beneath the cover.

Another object of the invention is to provide improved means for slidably mounting the curtain and to so mount this curtain that it may be frictionally held in a set position.

Another object of the invention is to so construct and mount the curtain that rods which form portions of the mounting frame 30 for the curtain may extend through coil springs carried by the curtain and thus the springs provide means for slidably mounting the curtain and also, by frictional engagement with the rods, provide means for holding the curtain in an adjusted position.

Another object of the invention is to so construct the curtain that the upper and lower end portions will be braced against transverse bending when moved upon the 40 rods.

Another object of the invention is to so construct this device that it can be applied to a conventional construction of automobile top.

45 This invention is illustrated in the accompanying drawings, wherein:

Figure 1 is a view showing an automobile in side elevation and provided with the improved curtain.

50 Figure 2 is a transverse sectional view taken along the line 2—2 of Fig. 1.

Figure 3 is a sectional view taken along the line 3—3 of Fig. 2.

55 Figure 4 is an enlarged view showing one of the curtains principally in elevation and partially in section.

Figure 5 is a vertical sectional view through the curtain taken along the line 5—5 of Fig. 4.

Figure 6 is a transverse sectional view 60 through the curtain taken along the line 6—6 of Fig. 4.

This improved curtain is used in connection with an automobile top of a conventional construction and indicated in general by the numeral 1. This top is carried by the body 2 of the automobile and is provided with doorways above the doors 3 of the body. For each doorway, a curtain will be provided and each curtain is slidably 70 mounted by means of a frame having side rods 4 which extend vertically at the sides of the doorway and have their upper end portions bent upon a curve and extended substantially horizontally beneath the cover 75 5 of the automobile top. The upper or inner end portions of these rods 4 are connected by a cross bar 6 and the outer or lower end portions of these rods are embedded in sockets formed in the body upon 80 opposite sides of the door 3. It will thus be seen that the curtain may be moved from an operative position as shown at the left hand of Fig. 2 to an inoperative position beneath the cover 5 as shown at the 85 right hand side of Fig. 2.

The curtain is provided with a transparent sheet 6 of isinglass or a similar material provided with side bindings 7 and upper and lower bindings 8 which are wider 90 than the side bindings. These bindings 7 and 8 are formed of water-proof fabric such as oil-cloth. Bracing strips 9 formed of celluloid, isinglass or any other suitable material are embedded in the bindings 8 so 95 that these bindings will be reinforced and prevented from being crumpled or bent out of shape when the curtain is in use. The bindings 7 overlap the end portions of the bindings 8 and extend beyond the side edges 100 of the transparent sheet 6 of isinglass or celluloid and provide pockets 10 in which the coil springs 11 would be mounted. The rods 4 pass through these coil springs as shown in Figs. 4 and 6 and the springs have 105 a binding engagement with the rods so that when the curtain is moved longitudinally upon the rods, the binding action of the springs will cause the curtain to be frictionally held in an adjusted position. If 110 desired a tab 12 may be provided at the lower end of the curtain so that the curtain

may be easily moved vertically into and out of an operative position.

When this device is in use, a curtain will be provided above each door of the automobile body 2 and in the touring car type of automobile shown in Fig. 1, there will be forward and rear curtains for the front and rear portions of the automobile, the front and rear curtains being positioned opposite each other as shown in Figs. 2 and 3. When it is desired to leave the doorways open above the doors 2 so that air can readily enter the automobile, the curtains will be moved upwardly to the inoperative position shown at the right-hand side of Fig. 2 and the springs will frictionally retain the curtains in the raised positions. When it is desired to have the curtains closed in order to shut out rain or to prevent cold air from entering the automobile, the curtain will be drawn downwardly to the position shown at the left-hand side of Fig. 2, in which position they will close the doorways above the doors 3 and thus effectively keep out cold air and rain but at the same time permit the occupants of the car to look out through the transparent sheets of celluloid 6. A curtain and mounting for the same has thus been provided which will be very simple in construction and very efficient in its operation and so constructed that it can be very easily put in place in connection with an automobile top of a conventional construction. If desired channel iron guiding strips may be secured at the sides

of the doorways above the doors 3 with the rods 4 extending through these channel iron strips to prevent danger of these strips being bent by wind pressure striking the curtains when in a lowered position. It should be further noted that the transparent sheet is protected at its upper and lower ends by channel strips 13 which prevent danger of tearing or creasing.

I claim:

A device of the character described comprising a curtain having a transparent sheet and bindings for the end and side portions of the sheet, the side bindings being formed of material folded longitudinally to provide longitudinally extending open ended pockets positioned beyond the sides of the transparent sheet and having extensions secured to opposite faces of the sheet, coiled springs extending longitudinally in the pockets, and a track structure having side rods each of an even diameter throughout its length and bent to provide a portion for extending transversely of a vehicle top in a substantially horizontal plane beneath the top and a portion for extending vertically from the horizontally disposed portion and passing through the pockets and springs to slidably mount the curtain with the springs tightly coiled about the rod to frictionally grip the same at any point and hold the curtain in an adjusted position.

In testimony whereof I have hereunto set my hand.

EMILE E. BOUCHARD.
